UNITED STATES PATENT OFFICE

137,750

DESIGN FOR A SCARECROW

Thomas Newhall, Lower Merion Township,
Montgomery County, Pa.

Application February 17, 1944, Serial No. 112,605

Term of patent 7 years

(CL. D1—2)

To all whom it may concern:

Be it known that I, Thomas Newhall, a citizen of the United States, residing in Lower Merion Township, in the county of Montgomery and State of Pennsylvania, have invented a new, original, and ornamental Design for a Scarecrow, of which the following is a specification, reference had to the accompanying drawing, forming part thereof.

Figure 1 is a plan view of a scarecrow, showing my new design.

Figure 2 is an edge view of the scarecrow shown in Figure 1.

I claim:

The ornamental design for a scarecrow, as shown.

THOMAS NEWHALL.
